Specification for Design.

Patented Jan. 30, 1912.

Application filed April 19, 1911. Serial No. 622,171. Term of patent 14 years.

To all whom it may concern:

Be it known that I, CHARLES E. THOMPSON, a citizen of the United States, residing at Troy, in the county of Rensselaer and State of New York, have invented a new, original, and ornamental Design for a Rubber Finger-Pad for Massage Devices, of which the following is a specification, reference being had to the accompanying drawing, forming a part thereof.

Figure 1 of the drawings is a view in per-

spective, as seen from above, of a rubber-finger pad embodying my design. Fig. 2 is a view in perspective, as seen from below, of the same.

I claim:

The ornamental design for a rubber-finger pad for massage devices as shown.

CHARLES E. THOMPSON.
